(74) Attorney, Agent, or Firm — Laurence A. Greenberg; Werner H. Stemmer; Ralph E. Locher

(57) **CLAIM**

I claim the ornamental design for a gymnastics apparatus, as shown and described.

DESCRIPTION

1.1 is a perspective view of a gymnastics apparatus showing my new design;

1.2 is an exploded view thereof;

1.3 is a top, front, right side perspective view of an anchor thereof;

1.4 is a bottom, rear, left side perspective view of the anchor;

1.5 is a top, front, left side perspective view of a frame thereof;

1.6 is a bottom, rear, right side perspective view of the frame;

1.7 is a right side view of the frame;

1.8 is a front view of the frame in a first height setting;

1.9 is a front view of the frame in a second height setting;

1.10 is a front view of the frame in a third height setting;

1.11 is a front view of the frame in a fourth height setting;

1.12 is a top, front, left side perspective view of a support plate thereof; and

1.13 is a bottom, rear, right side perspective view of the support plate.

The broken line showing of a support belt, a slackline,

1.2 is for the purpose of illustrating environmental structure and forms no part of the claimed design.

1 Claim, 13 Drawing Sheets
